(57) **CLAIM**

We claim the ornamental design for a package for a location tracker for an item, as shown and described.

DESCRIPTION

FIG. 1 shows an isometric view of a package for a location tracker for an item.

FIG. 2 shows front view of the package of FIG. 1.

FIG. 3 shows a back view of the package of FIG. 1.

FIG. 4 shows a left side view of the package of FIG. 1.

FIG. 5 shows a right side view of the package of FIG. 1; and, FIG. 6 shows a plan view of the package of FIG. 1.

A rearward side of the package is not shown and is not part of the claimed invention.
